UNITED STATES PATENT OFFICE.

MOISE LANDRY, OF MERCED, CALIFORNIA.

ELECTRIC HEATER.

No. 873,317.

Specification of Letters Patent.

Patented Dec. 10, 1907.

Application filed March 27, 1907. Serial No. 364,748.

To all whom it may concern:

Be it known that I, MOISE LANDRY, a citizen of Canada, residing at Merced, in the county of Merced and State of California, have invented a new and useful Electric Heater; and I do hereby declare the following to be a full, clear, and exact description of the invention, such as will enable others skilled in the art to which it appertains to make and use the same.

This invention relates to electric heaters.

It has for an object to provide an electric heater which is portable and which is adapted to be used as a foot warmer in a bed, an electric automobile or the like.

A further object is to provide a device of this character which is inexpensive to manufacture and simple in operation.

With these and other objects in view the invention consists of the parts and combination of parts, hereinafter described, more particularly pointed out in the appended claims and shown in the accompanying drawings.

Figure 1 is a plan view of the invention. Fig. 2 is a side view. Fig. 3 is a view showing the heater open and Fig. 4 is a longitudinal sectional view.

Referring more particularly to the drawings, A and B indicate a pair of heating elements. These elements each comprise a board 1 of thin wood veneer covered by sheet asbestos 2 cemented, tacked or otherwise secured to the board. These heating elements are hinged together each along one of its longitudinal edges by hinges 3 which, when the elements lie one upon the other, do not project beyond the device. The purpose of this is to prevent one being injured by the hinges when it is used in bed as a foot warmer. The elements are secured in their folded position by fastenings 4 which also do not project beyond the heater.

Secured to the inner face of one of the elements, is a resistance wire 5 which is bent into coils extending longitudinally of the

heater. Any suitable means may be employed for securing the wire in place. The two ends of the resistance wire are secured to small binding posts. The binding posts 50 are each formed by providing two washers 6 and 7 one on each side of the board, and connecting the washers by an internally and externally threaded insulating sleeve 8, a brass bolt 9, serving to hold the ends of the 55 current wire 10 into contact with the end of the resistance wire, both wires being twisted.

The veneer being very thin, conducts the heat from the resistance wire and the asbestos prevents any danger from fire by preventing the heater becoming too hot. The binding posts being arranged between the elements, prevent one from receiving shocks by unconsciously placing a foot upon them while sleeping.

The current wires 10, are provided with a socket plug 11 so that the heater may be carried from place to place.

Having thus described my invention, what I claim and desire to secure by Letters-Pat- 70 ent is:

A portable electric heater, comprising two wood veneer boards covered with asbestos and hinged together, fastening devices for securing the boards together, a resistance 75 wire between the boards, binding posts arranged between the boards comprising washers disposed upon opposite faces of the boards and internally and externally threaded insulating sleeve, extending through the 80 board and the washers, and a thumb bolt engaging the internal thread and serving to hold the ends of the current wire, while the lower washers serve to hold the resistance wire as and for the purpose specified.

In testimony whereof I have signed my name to this specification in the presence of two subscribing witnesses.

MOISE LANDRY.
